FIG. 5.

Inventor
Joseph D. Harris

By Eugene Curran Atty.

UNITED STATES PATENT OFFICE.

JOSEPH D. HARRIS, OF DETROIT, MICHIGAN, ASSIGNOR, BY MESNE ASSIGNMENTS, TO
MCCORD RADIATOR & MFG. CO., OF DETROIT, MICHIGAN, A CORPORATION OF MAINE.

TINNING MACHINE.

Application filed January 28, 1922. Serial No. 532,485.

This invention relates to a machine for coating with metal, as tin solder by a continuous process the metal band or ribbon stock used for making tubes for automobile radiators or for other purposes.

One object of my invention is to provide a machine for coating simultaneously both sides of the metal band or ribbon stock as it is fed through the machine and thus provide solder in the lock seam when the coated band is made into radiator tubes.

Another object of my invention is to so construct the machine that it may be readily used between and in conjunction with the flux bath at one end and the tube forming mechanism at the other end of the machine, so that the metal band or ribbon stock may be coated as fast as it is fed into the tube forming mechanism and thus coat the band and form the tubes by a continuous and uninterrupted process.

A further object of my invention is to provide means for controlling the thickness of the coating layers applied to the ribbon or band and thus permit coatings of a predetermined thickness to be applied to the stock.

Other and further objects of my invention will appear from the following specification, taken in connection with the accompanying drawings, in which—

Fig. 1 is a longitudinal sectional view taken through a coating machine constructed in accordance with my invention;

Fig. 2 is a top plan view of said machine; Figs. 3 and 4 are transverse vertical sectional views taken on lines 3—3 and 4—4, respectively, of Fig. 1; and

Fig. 5 is a longitudinal vertical sectional view taken on line 5—5 of Fig. 2.

As shown in the drawings, the machine of my invention comprises an elongated, upwardly opening tank 1, supported above a floor or other underlying surface by a suitable framework, comprising horizontal side members 2, 2 and vertical end members or legs 3, 3. Said tank 1 contains a bath of coating metal, as tin solder maintained in molten condition during the use of the machine by any suitable heating means associated with the tank. This means, as illustrated in the drawings, comprises a gas burner pipe 4 extending beneath the bottom wall of

the tank and supported between the legs 3 thereof, as shown.

Extending across and secured to the side members 2, 2 at one end of the machine is a cross bar 5 having upwardly projecting bearings 6, 6 for a horizontally arranged shaft 7. One end of this shaft 7 projects beyond the adjacent side of the machine, and to it is fixed a pulley 8 whereby the shaft may be rotated. Arranged above the tank 1 is a frame having side members 9, 9, these being connected together at one end by a cross bar 10. The members 9 at the other ends are mounted on the shaft 7 in a manner to permit the frame to be raised and lowered with respect to the tank, as shown in dotted lines in Fig. 1.

Extending between and journaled in the side members 9, 9 are two shafts 11, 12 having at their ends, over the tank 1, rolls 13, 14, respectively. For rotating these rolls in the direction desired, such as indicated by the arrows in Fig. 5, I provide a sprocket chain 15 looped about a sprocket wheel 16 on the shaft 12 and looped about a sprocket wheel 17 on the shaft 7. The lower lap of the chain runs over a sprocket wheel 18 on the shaft 11, and the upper lap of the chain runs over a grooved idler roller 19 on an arm 20 adjustably secured to the adjacent side member 9 of the frame, as shown in Fig. 5.

Secured to the other side member 9 of the frame in line with the rolls 13, 14 and on opposite sides thereof are the angle-plates 21, 22, arranged as shown in Figs. 2 and 3, for holding against their respective rolls 13, 14 blocks 23, 23 of salammoniac or equivalent material to prevent oxidization of the tin carried by the surfaces of said rolls. These blocks also wipe off surplus solder from the rolls 13, 14 and maintain the same clean.

In Fig. 1, I have indicated the metal band or ribbon stock to be coated by my machine, by the numeral 24 extending from a flux cleaner (not shown) over a roll 25 of that mechanism, which roll is supported in suitable manner above the machine herein shown and at the end of the tank 1 opposite the driving pulley 8. The ribbon or band 24 is carried down into the tank 1, to be submerged into the bath of hot coating metal

contained therein and led under a roll 26 on a shaft 27 maintained in clip shaped brackets 28 secured to the side members of the machine, as shown in Fig. 2.

5 The roll 26 is in line with the rolls 13, 14, which are in alignment with each other and dip down into the metal bath. The band 24 after leaving the roll 26, is threaded under the roll 14 and extends up between the 10 rolls 13 and 14 and over the top of the latter and on to a tube forming machine (not shown). The rolls 13 and 14 have the same diameter and by rotating downward and away from the band as it is progressed between the rolls serves to cause a substantially uniform coat of metal to be applied to both sides of the band or ribbon 24 as the rolls wipe off the surplus coating metal which is naturally drawn up by the band on passing between these rolls. The band is fed through these rolls by suitable feeding, rolls of the tube forming machine, and consequently the rolls 13 and 14 of my coating machine may be driven mechanically in a direction against the movement of the band between the same, as these rolls do not act to progress the band through the metal bath.

To facilitate threading the band or ribbon 24 between the rolls 13, 14 and over the former, the frame carrying the rolls 13, 14 is raised above the tank to lift the rolls out of the metal bath and thus permit the threading of the band or ribbon between the rolls without dipping down into the bath or emptying the tank, as indicated by dotted lines in Fig. 1. To enable the frame 9 to be lifted, I provide a vertically movable bar 29 arranged to the rear of the machine, as shown in the drawings, and slidably connected with the rear side member 2 of the machine, there being a pin 29^a on the frame member 2 and slot 29^b in the bar for this purpose, as shown in dotted lines, in Fig. 1. The upper end 30 of this bar is offset inwardly and upwardly to come substantially midway between the side members 9 of the frame carrying the rolls 13, 14, and this end is bifurcated or slotted, as shown in the drawings, to engage the cross bar 10 of said frame. The lower end of the member is pivoted to a foot pedal 31, which in turn is pivotally mounted between its ends to a suitable bracket 32 resting on the floor. The operator on depressing the pedal 31 by his foot raises the frame carrying the rolls 13, 14 up out of the metal bath to a position for threading the metal band or ribbon between them, as heretofore mentioned.

60 By the machine shown and described, the metal ribbon or band, usually made of brass, is coated on both sides with tin or solder and about the edges thereof. Thus solder is both inside and outside of the crimped seam of the tubes formed from said band, edgewise between said rolls.

and proper leak proof joints made when said seam is soldered during the manufacture of the radiator. Moreover, coating of the metal stock is carried on as fast as the material is fed into the tube forming mechanism, thus increasing production and only coating the stock as needed. The band 24 being moved through the machine by the feed in the tube forming mechanism or mill, carries the band through the metal bath at the speed required for the tube mill and at the tension best suited for applying metal thereto. The feed not being in the tinning machine, makes possible the rotation of the rolls 13, 14 mechanically and in a direction against the movement of the band without being in gripping engagement therewith. This enables a proper application of coating to the band, and permits placing the rolls 13, 14 close enough together to regulate the thickness of the coating layers on the band and thus prevent the application of surplus material. The fact that the rolls 13, 14 may be raised out of the metal bath facilitates threading a band in the machine.

While I have shown and described herein in detail a machine of my invention, it is to be of course understood that the details of construction and arrangement of parts shown may be variously changed and modified without departing from the spirit and scope of my invention.

I claim as my invention:

1. In a machine for coating metal band or ribbon stock with metal, the combination with a bath of molten metal, of means adjacent the inlet end of the bath for guiding said band into the same, a pair of inner and outer smoothing rolls held out of gripping engagement with the band and located at the delivery end of the bath with their lower portions partially submerged therein, said band passing under and contacting with the lower periphery of the inner roll and passing over and contacting with the upper periphery of the outer roll after passing between said rolls, and means for positively rotating said rolls in directions opposed to the direction of travel of said band between them for making smooth and even the metal coatings on the band.

2. In a machine for coating metal band or ribbon stock with metal, the combination with a bath of molten metal, of means at the inlet end of the bath for guiding the band into the same, a pair of smoothing rolls at the delivery end of the bath and in contact with both sides of the band, said rolls being partially submerged in the bath and held out of gripping engagement with the band, means for positively rotating said rolls in directions opposed to the travel of the band between them, and means for raising the rolls out of the bath for inserting the band

3. In a machine for coating metal band or ribbon stock with metal, the combination of a tank to contain a bath of molten coating metal, a pivotally mounted frame on said tank, rolls carried by said frame and partially submerged in the metal bath, said rolls being spaced apart for the band to pass between them on leaving the metal bath, means for rotating said rolls relatively to said band as the latter passes between the same for making smooth and even the metal coatings on the band, and manually operable frame raising means whereby the rolls may be lifted out of the metal bath to permit insertion of the band edgewise therebetween. 40
4. In a machine for coating metal band or ribbon stock with metal, the combination of a tank to contain a bath of molten coating metal, a main driven shaft journaled above said tank, a frame pivoted on said shaft, two shafts journaled on said frame, rolls on said two shafts and rotated thereby, said rolls being spaced apart for the band to pass therebetween on leaving the metal bath, a sprocket wheel on each of said shafts, a sprocket chain trained over said sprocket wheels in a manner to rotate said rolls against the direction of movement of the band between said rolls, and means for moving said frame upwardly whereby the rolls may be raised out of the metal bath. 45
5. In a machine for coating metal band or ribbon stock with metal, the combination of a tank to contain a bath of molten coating metal, rolls partially submerged in the metal bath and spaced apart for the band to pass between them on leaving the metal bath, members supporting salammoniac blocks in wiping contact with said rolls, and means for rotating said rolls against the direction of movement of the band between said rolls. 50
6. In a machine for coating metal band or ribbon stock with metal, the combination of a tank to contain a bath of molten coating metal, a frame above said tank, rolls carried by said frame and partially submerged in the metal bath, said rolls being spaced apart for the band to pass between them on leaving the metal bath, plates carried by said frame on opposite sides of said rolls for supporting blocks of salammoniac in wiping contact with said rolls, and means for rotating said rolls against the direction of movement of the band between said rolls. 55
7. In a machine for coating metal band or ribbon stock with metal, the combination of a tank to contain a bath of molten coating metal, an upwardly movable frame above said tank, two rolls carried by said frame and partially submerged in the metal bath, said rolls being spaced apart for the band to pass between them on leaving the metal bath, means for rotating said rolls against the direction of movement of said band between them for making smooth and even the coatings on the band, a vertically movable rod having its upper end engaged with said frame for raising the same and lifting the rolls out of the metal bath, and a depressible foot treadle connected with the lower end of said rod for raising the same. 60

In testimony that I claim the foregoing as my invention, I affix my signature this 24 day of Jan., A. D. 1922.

JOSEPH D. HARRIS.
